UNITED STATES PATENT OFFICE.

JOHN M. WILSON, OF SAN DIEGO, CALIFORNIA.

DENTAL APPLIANCE.

Application filed April 18, 1922. Serial No. 554,685.

To all whom it may concern:

Be it known that I, JOHN M. WILSON, a citizen of the United States, and resident of San Diego, in the county of San Diego and State of California, have invented certain new and useful Improvements in Dental Appliances, of which the following is a specification.

My invention relates to dental appliances, and has particular reference to improvements in devices for holding upper and lower dentures in place.

In a general way my improved device is similar to existing devices of the type mentioned in that it consists essentially of a spring adapted to be bowed intermediately and secured at its respective ends to upper and lower dentures whereby it imparts a force acting to hold the dentures in place. It is an improvement over such existing devices, however, because it does not irritate or lacerate the tender tissues of the inner side of the cheek; because it cannot buckle forward and thus cease to function; because in its applied position it hugs the sides of the dentures closely and occupies a minimum amount of space; because it includes a protective covering or guard over the pivotal connection of the ends of the spring with the dentures, which acts to limit the angular movement of said pivotal connections and thereby maintains the device as an entirety properly in place, and because all of the foregoing advantages are combined in a structure which is simple, inexpensive and easy to produce and apply.

My inventive idea is capable of embodiment in different mechanical structures, one of which is illustrated in the accompanying drawings, but it is to be understood that the structure shown is merely intended as a disclosure of the essential features and novel characteristics of my invention in a preferred form and that its scope is as defined in the appended claims.

In the drawings wherein like characters of reference denote corresponding parts in the different views—

Figure 1 is a side elevation showing the application of my improved device to upper and lower dentures;

Fig. 2, a detail vertical section showing the manner of connecting my improved device with the dentures;

Fig. 3, an enlarged elevation of the inner 55 face of one of the pivot bars and its guard;

Fig. 4, a detail horizontal section showing the manner of connecting my improved device with the dentures;

Fig. 5, an enlarged detail perspective of 60 one of the pivot bars;

Fig. 6, a cross section showing the shape of the free end portion of the pivot bars;

Fig. 7, an enlarged detail perspective of 65 one of the guards; and

Fig. 8, an enlarged detail perspective of a portion of the spring.

Referring now to the drawings in detail, it will be observed that my improved device includes, essentially, an elastic element 70 10 preferably in the nature of a coil spring which is adapted to be bowed intermediately and secured at its respective ends to upper and lower dentures 11 and 12 whereby it imparts a force acting normally to urge the 75 dentures apart and thereby hold the same in place. Desirably two of these flexible elements 10 are provided for each pair of dentures 11 and 12 and they are adapted to be secured to the outer faces of the dentures 80 upon opposite sides thereof as is usual in appliances of this kind. Only one of the elements 10 has been illustrated, however, as they are duplicates of each other and a showing and description of either, therefore, will suffice for both.

As a desirable and convenient means of pivotally connecting the respective ends of the spring 10 to the dentures 11 and 12, I provide a pair of bars 13, a pair of ordinary 90 securing screws 14, and embed in each denture a nut or other threaded member 15. The bars 13 are of duplicate construction and each of them includes at one end an eye 16 having an opening through which a 95 screw 14 is adapted to be passed and threaded into a member 15 whereby the bars are pivotally connected to the dentures. When the bars have thus been secured to the dentures, the coil spring is bowed intermediately and engaged at its ends over said bars.

By particular reference to Figures 6 and 8 of the drawings it will be observed that the spring 10 in cross section is formed with a rounded outer face and a flat inner face 105 so that it may closely hug the dentures and thereby occupy a minimum amount of space. Its outer face is rounded and therefore is

unlikely to irritate the soft tissues of the inner face of the cheek. The inner face of each bar, like the spring 10, is provided with a continuous inner flat face and adjacent to its free end with a rounded outer face, while towards its pivot end its outer face is also flattened as shown. This construction permits snug engagement of the bars against the dentures and also snug engagement of the ends of the spring with the bars, and at the same time provides for the accommodation of guard plates 17, one of which is adapted to be secured in covering relation to each pivot. The guard plates are in the form of housings adapted to embrace the eyes of the bars 13 and each includes a fan-shaped protective portion 18 adapted to overlie its related bar and hold it close to the denture thereby avoiding the free play which is usual in devices of a like nature, the sides of said fan-shaped portion being provided with webs 19 for limiting the angular movement of the bars about their pivots. The guards may be secured in place in any desired manner, but it is preferred to utilize the screws 14 for this purpose and to this end each guard is provided with an aperture through which a screw 14 may be passed prior to engaging the same through the eye of a related bar 13.

From the foregoing description and drawings it is apparent that I have provided an improved dental appliance capable of accomplishing the various advantages previously outlined and while I have disclosed the same in association with full upper and lower sets of teeth, it is manifest that its utility is not thus limited, as it may with facility be used in connection with partial dentures, removable bridge work and telescoping crowns. It is further more apparent that regardless of its use, my device as an entirety closely hugs the dentures, yet is free to swing and serve its desired function, and that the guards not only protect the tissues of the cheek from the pivots, but also, be-

cause of the webs 19 eliminate the possibility of the spring 10 buckling forward.

I claim:—

1. A dental appliance comprising upper and lower dentures, and a coil spring bowed intermediately and secured at its respective ends to said dentures whereby the latter normally are urged apart, the inner face of said spring being flat thereby to lie closely against said dentures. 50

2. A dental appliance comprising upper and lower dentures, a pair of bars secured respectively to said dentures, the inner face of each bar being flat thereby to lie closely against its associated denture, and an intermediately bowed spring having its ends fitting over and secured respectively to said bars whereby the dentures normally are urged apart, the inner face of said spring 60 being flat thereby to conform in shape to said bars and to lie closely against said dentures. 65

3. A device for holding dentures in place including an elastic element adapted to be intermediately bowed and pivotally connected at its respective ends with upper and lower dentures, a guard covering the pivot of said flexible element with each denture, and means included in said guard to limit 70 the angular movement of said pivotal connections. 75

4. A device for holding dentures in place including a pair of bars adapted to be pivoted, respectively, to upper and lower dentures, an elastic element adapted to be bowed intermediately and secured at its respective ends to said bars, and a guard covering the pivotal connection of each bar with its related denture, each of said guards including a fan-shaped extension overlying its associated bar, and each extension having side walls limiting the angular movement of its associated bar about its pivot. 80 85

In testimony whereof I hereunto affix my signature. 90

JOHN M. WILSON.
